UNITED STATES PATENT OFFICE.

EINAR J. NELSON, OF TACOMA, WASHINGTON.

DESIGN FOR A BARBER'S COMBINATION WORK-TABLE.

56,186.

Specification for Design. Patented Aug. 24, 1920.

Application filed May 11, 1920. Serial No. 380,672. Term of patent 7 years.

To all whom it may concern:

Be it known that I, EINAR J. NELSON, a citizen of the United States, residing at Tacoma, in the county of Pierce and State of Washington, have invented a new, original, and ornamental Design for Barbers' Combination Work-Tables, of which the following is a specification, reference being had to the accompanying drawing, forming part thereof.

The figure is a perspective view of a barber's combination work table showing my new design.

I claim:

The ornamental design for a barber's combination work table, as shown.

EINAR J. NELSON.
